CHARLES H. HAWKINS, OF FREEPORT, NEW YORK, ASSIGNOR TO STANDARD OIL COMPANY OF NEW YORK, OF NEW YORK, N. Y., A CORPORATION OF NEW YORK.

CANDLE-MAKING MACHINE.

1,271,512.

Specification of Letters Patent.

Patented July 2, 1918.

Application filed June 30, 1917. Serial No. 178,023.

To all whom it may concern:

Be it known that I, CHARLES H. HAWKINS, a citizen of the United States, and a resident of the town of Freeport, in the county of 5 Nassau and State of New York, have invented a new and useful Improvement in Candle-Making Machines, of which the following is a specification.

It is the purpose of this invention to so 10 construct the operative parts of the machine that it shall be adapted to the rapid, inexpensive and accurate manufacture of candles of very small size, variously known as birthday candles, toy candles, Christmas candles, 15 and the like. Prior to my invention it has been found in the practical manufacture impossible to make candles of a smaller diameter than about five sixteenths of an inch, and in order that a candle of that diameter shall 20 present an attractive appearance, it is necessary that its length shall bear the proper relation to its diameter, with the result that a candle of such size will burn for approximately half to three quarters of an hour, 25 too long a time for the most acceptable use upon a birthday cake, or similar social occasion, so that a demand has arisen for candles of much smaller size, both in diameter and length, which will present a more attractive 30 because so to speak cunning appearance and which will burn out or be consumed in practically ten or twelve minutes, which will be the most acceptable period of illumination, and also will permit a greater number 35 of candles and their appropriate holders in a given space than was possible with candles as heretofore constructed for this purpose and are also more desirable where weight is a consideration.

40 Yet, notwithstanding the demand, it has been found impractical to make candles of such small size, say three sixteenths of an inch in diameter and about two inches or thereabout in length with the ordinary candle making machines, so that it has been customary to make them from wax tapers which were cut into sections and then as a somewhat expensive, because time making 45 process, fashion at one end of each section the igniting end of the candle with protruding wick, so that they can be quickly and conveniently lighted at the time of use. My invention, therefore, relates to a machine, 50 certain parts of which are old and well known and certain parts new, whereby can-

dles of the diameter and length desired, however small, may be rapidly and inexpensively produced in large quantities.

In the drawings, Figure 1 is a sidewise elevation of the machine, the parts being 60 broken away and certain parts omitted; Fig. 2 is an endwise elevation of that which is shown in Fig. 1; Fig. 3 is a vertical sectional view of one of the candle forming molds, showing the movable plunger therein. 65

Referring to the drawings, 1 represents the frame of the machine, 2 the usual water tank, 3 the usual wax tray, 4 the water inlet pipe, 5 the water exit pipe, 6 a crank, or equivalent source of power, whereby 70 through the usual set of gearing 7, 8, 9, 10 and 11, the usual rack bars 12 and 13, and the transverse shaft 14, the plunger carrying plate 15 (see Fig. 1) is lifted and depressed. It will be understood of course that the 75 train of gearing above referred to occurs at both sides of the machine, the set opposite the crank being actuated by the counter shaft 14, and that the racks 12 and 13 engage with each corner of the plunger supporting 80 and operating plate 15.

Supported at their lower end upon the bottom of the water tank and at their upper end in the bottom of the wax tray, are a series of candle molds 16, preferably provided with suitable packing 17 and nut 18, so as to secure a tight joint at the bottom, and with suitable threading 19 in the bottom of the wax tray at the top. The upper ends of these molds are flush with the bottom of the tray. There are a great number of these molds, several hundred, even a thousand or more in each machine. They are placed close together. A vertical hole is made through the upper part of each of the 95 molds of such diameter as will equal the diameter of the desired candle and within each mold a vertically movable plunger 20 is arranged. It is enlarged as shown at 21 at its upper end and within the enlarged 100 portion and extending downwardly somewhat therefrom, molten metal 22, of suitable character, preferably block tin, is poured during the construction of the plungers, and is thereafter machined in such manner as to 105 produce the desired shape of the ignition end of the candle, a desirable shape being shown in Fig. 3. Also a central hole is bored through the block tin, or equivalent material, through which the wick 23 passes, 110

and below the block tin, or other filling 22, the wick extends through the hollow plunger 20, projecting below its lower end, and proceeds thence downwardly to a spool, bobbin, or shaft, upon which the wicks are wound. The vertically movable plungers 20 are each supported at their lower end by the vertically movable plate 15, as shown in Fig. 1, each of the plungers having an enlargement 24 at its lower end which fits somewhat loosely within the recess 25 made in the plate 15, so that the plungers may be capable of slight freedom of movement in their passage through the lower part of the mold. Their stems or spindles are somewhat smaller than the hole in the lower part of the molds through which they move, thus avoiding the considerable power that would be necessary to elevate and depress the plate 15 and the multitude of plungers carried by it, if they had even approximately a tight fit. It will of course be understood that the construction above described is present at each of the many molds in the machine; so that each is supplied with its own vertically movable plunger carrying the wick for the individual candle to be made in each mold as described.

The operation is as follows: Assume that the driving mechanism has been so manipulated that the plate 15 carrying with it all the plungers has descended to the lowest point, so that the parts are in the position shown in Fig. 3, in which it will be noted that the enlarged upper end 21 of each plunger fits snugly against the contracted lower portion of the candle molding section in each of the molds after the fashion of a check valve, thus effectually sealing the joint 40 against downward movement of the wax.

The tank 2 is normally filled with water, alternately hot or cool, and it will be noted that the water inlets and outlets are large, so that the volume of water which continually passes through the apparatus is sufficiently large to effect quick warming and cooling of the apparatus.

As the first operation, hot water is introduced through the water supply pipe 4, which promptly expels the relatively cool water formerly in the tank 2 through the overflow 5. Within a minute or two all of the molds 16 are sufficiently heated by the incoming hot water. Thereupon an attendant pours into the wax tray 3 a sufficient amount of melted wax to fill all the candle molds and in order to assure this result his experience guides him in distributing the melted wax over the bottom of the wax tray 55 in such manner that after all the molds have been filled, there shall be a film of perhaps an eighth or a quarter of an inch in thickness of the wax upon the bottom of the tray, thus assuring the complete filling of the 60 molds. Thereupon the supply of wax is cut

off, the hot water supply is also turned off and the cold water turned on, and it in turn quickly expels the hot or at least warm water from the tank 2 and quickly chills each of the molds between and through 70 which it rapidly circulates. As soon as the molds have become sufficiently cooled to set the wax, the cold water is in turn shut off and the operator then preferably using a steel tool known as a "topping knife" and 75 which roughly resembles a dust pan, or flattened scoop, the edge of which is sharpened, and which preferably somewhat accurately fits the bottom of the wax tray, slices off the excess wax from the bottom of 80 the tray, in so doing slicing off also the butt ends of all of the candles and the excess of wick, leaving the end of the candles flush and square with the bottom of the wax tray. The excess wax and remnants of wicking are received in the scoop-like knife and by the operator thrown into a suitable place of deposit for re-melting and straining. The operator then turns the crank 6, which lifts the plate 15, carrying up with it all of 90 the many plungers 20, each of which pushes upward through the now empty wax tray the candle made in the mold to which it belongs and in so doing also unwinding from the wick spool, bobbin or shaft an appropriate amount of wick for the next succeeding candle. The candles projected upwardly from the upper ends of the plungers, as stated, in due course engage with the usual candle supporting and holding racks, 100 which since they form no part of this invention and are well understood have not been illustrated.

Thereupon the operator reverses the crank 6, the plate 15 descends carrying with it all of the plungers, which again attain their primary position shown in Fig. 3, leaving the wick 23 projecting upwardly through each of the molds, and still attached to each of the candles, so that they are held in perfect vertical alinement. The operation of filling the molds is repeated and the second batch of candles produced. As soon as they have become chilled, a suitable, keenly sharpened and long bladed knife is passed 110 across the under surface of the candle holding racks above referred to, whereby all of the wicks are cut off at the desired distance from the ignition end of each candle.

I call particular attention to the plungers 120 because their construction, simple as it may seem, is a matter of great importance in the manufacture by machine of the extremely small candles here referred to. It is essential that the stem part of these 125 plungers shall be small, not materially larger than a straw because they must pass freely and without any binding action whatever through the small opening made in the lower part of each of the molds and this 130

opening must be materially smaller than the size of the candle to be made in the mold because it is necessary that there be a shoulder at the bottom of the candle bore 5 of the molds to act as a seat for the enlarged or bell shaped part of the plungers to act as valves to prevent the hot wax from passing downwardly into the contracted passageway below, which would quickly clog 10 the entire apparatus, and not only must the plungers themselves be small, not larger than a straw, as I have said, but they must be hollow in order that the wick may pass up through them. Therefore since it has 15 been found practically impossible to bore a brass or copper wire from end to end with a hole so small as to permit the passage of the wick, and then machine the outer side of the rod or wire to reduce it to proper dimension, the only feasible way of making 20 the plungers is that invented and illustrated by me, that is to say, I take a good quality brass tubing of a suitable size and carefully expand one end into the bell shaped terminal 25 21, as shown in Fig. 3, and then fill the bell shaped enlargement and so much of the tubular portion adjoining it as desired with a suitable non-corroding metal, preferably block tin because it has but little tendency 30 to expand and contract under changes of temperature, and after the block tin is cooled, I machine it to the shape shown in Fig. 3, or other desired form, leaving a central hole therein sufficiently large to receive 35 the wick.

It will be obvious to those who are familiar with such matters that departures may be made from the details of construction and method of operation described by me and 40 still the essentials of the method and of

the machine be employed. I therefore do not limit myself to the details of that which I have above described and illustrated.

I claim:

1. A plunger for candle making molds 45 adapted for the manufacture of toy candles, comprising a longitudinally hollow stem smaller than the part of the mold through which it moves, an enlarged cup shaped member at the upper end of the stem and 50 integral therewith, and a lining for the cup shaped member of noncorrosive metal immovably attached thereto, so machined as to conform to the ignition end of the candle and perforated to permit the passage of the 55 wick therethrough.

2. In a candle making machine a longitudinally hollow mold the bore whereof has two diameters, the upper part being of the same diameter as the candle and the lower 60 part of less diameter, a plunger adapted to work within said mold comprising a longitudinally hollow stem smaller than the part of the mold having the lesser diameter, an enlarged cup shaped member at the upper 65 end of the stem and integral therewith and adapted to substantially fit the part of the mold having the larger diameter but too large to enter the part having the lesser diameter, and a lining for the cup shaped 70 member of noncorrosive metal immovably attached thereto, so machined as to conform to the ignition end of the candle and perforated to permit the passage of the wick therethrough, the lower end of the stem of 75 the plunger being loosely connected with a vertically movable plate or frame.

In testimony whereof I have signed my name to this specification.

CHARLES H. HAWKINS.
